UNITED STATES PATENT OFFICE.

JOHN J. EVERSON, OF NEWTON, MASSACHUSETTS.

ARTIFICIAL LIMB.

1,369,016.

Specification of Letters Patent. Patented Feb. 22, 1921.

Application filed July 24, 1917. Serial No. 182,440.

To all whom it may concern:

Be it known that I, JOHN J. EVERSON, a citizen of the United States, and a resident of Newton, county of Middlesex; and Commonwealth of Massachusetts, have invented 5 an Improvement in Artificial Limbs, of which the following description, in connection with the accompanying drawings, is a specification, like characters on the drawings representing like parts.

This invention relates to artificial limbs, and its aim is to provide an improved limb, and particularly a hand, having what may be termed unusual gripping or muscular 15 power with great muscular flexibility.

My invention as illustrated and described herein, is embodied in a hand and in the drawings.

Figure 1, is an inside view; 20 Fig. 2, an outside view or back of the hand;

Fig. 3, an end view showing particularly the knuckles;

Fig. 4, a vertical sectional view of one of 25 the fingers, and

Fig. 5 is a diagrammatical illustration of the position naturally assumed by the muscles of the fingers before they are incased in the felt covering or body.

30 My novel construction of artificial hand comprises a body 1, which may be of any suitable material, preferably wool felt, as the most sanitary, of convenient weight and texture to give it the necessary firmness, and 35 terminating at its inner end in an arm or sheath 2, of proper length to receive the stump or end of the severed arm.

The body 1 of the hand may be formed 40 from two layers of felt stitched together at their edges or from one piece, properly slit to permit the formation of the fingers 3 and sewed together at the edges of the slit portions, the seams conveniently being made on the opposite sides of the fingers so that 45 many of them are hidden by the adjoining fingers. If desired, the fingers may be saturated with shellac or liquid rubber and sandpapered to improve their appearance.

The sheath is also formed herein by sewing, not shown, together the edges of the 50 felt member 2, in this case the seams on the outside of the thumb and little finger respectively, being continued the length of the sheath.

55 To provide the fingers with the desirable

flexibility and gripping qualities, they are each so far as desired, provided with a resilient muscle 4, herein of stiff wire.

I prefer to provide each finger 3 with a muscle 4, and find that it may be done 60 satisfactorily by the use of a long wire member or muscle as 5.

Referring to Figs. 1, 2, it will be seen that muscle 4, of the forefinger, and muscle 4 of the second or middle finger are formed 65 from the wire or muscle 5, extended substantially the length of the sheath and nearly around the upper end thereof and suitably anchored thereto as by stitching the muscle down against and to the sheath.

70 I prefer to form a groove 6 in the sheath for the muscle 5 either by suitably compressing the same, or by cutting out a portion of the felt so that the muscle may be partly, at least, countersunk therein, down as far as 75 the wrist. By this means the muscle is less noticeable to the touch.

Likewise the muscles 4 for the third and little fingers are formed by the wire 7, also 80 extended substantially the length of the sheath, and secured thereto in the same manner as wire 5. By forming the muscles for the fingers from or connecting them with the long muscles 5, 7, the finger muscles are firmly anchored and capable of carrying 85 great weight and have unusual lifting power; they are also prevented from turning or from becoming loose. At or about the wrist portion 8 I prefer to embed the wire muscles 5, 7, in the felt or body 1, and, 90 to assist in holding the wires in position in the fingers, I cut away portions thereof or form grooves therein on the inside to receive the wires, as in the case of the sheath 2.

To give great flexibility to the fingers, 95 which is so greatly desired, I have conceived the novel plan of forming a spiral section 9 in each muscle in the body of the hand. This spiral gives unusual elasticity and flexibility to the fingers, and permits the 100 use of them in many ways and for several purposes for which the fingers would otherwise be unavailable.

For instance, it will be obvious that a certain longitudinal motion or lengthening 105 of the fiber fingers will be possible under certain strains with the coiled spring or muscle sections 9, which would not otherwise be the case if the muscle 4 simply was capable of being bent or flexed forward, the 110

coil feature in the former case permitting a limited longitudinal motion of the fingers beyond the body of the hand.

Furthermore, by this means I am able to 5 impart greater flexibility to the fingers for lateral motion with the same rigidity or gripping quality for holding things between the fingers.

To increase the lateral gripping power of 10 the fingers, I prefer to give the ends or tips of the muscles 4 an initial tension toward each other, and in this case I have shown the muscles of the fore and middle fingers with a tension tending to turn them toward the 15 third finger, and have shown the third and little fingers with a tension tending to turn them toward the fore and middle fingers, thus providing great gripping powers between any two of these fingers.

20 To give the required flexibility to the thumb so that it can be moved in any direction, this being more necessary in the case of the thumb than the power of gripping or lifting, I provide the thumb with a 25 muscle, of which the coiled portion extends nearly to the outer end, the straight portion or tip being shorter, thus providing the flexibility which permits bending the thumb in any direction, making it more serviceable.

30 The thumb may be bent completely under the forefinger, thus making it very easy to grip between the thumb and forefinger tools, such as chisels, and also to carry similarly shaped articles as lead pencils or pens there- 35 between, and firmly held in position.

For attaching the sheath to the arm, Figs. 1, 2, straps 10 or any other convenient means may be provided, and they are preferably secured to the muscles 5, 7, thus anchoring 40 them firmly to the wearer's body for security and lifting power. Felt is far superior to any of the articles now in use for that purpose, so far as I am aware. Leather and wood, so generally used, are both unsanitary as from the nature of the materials they 45 offer no means for circulation of air, and

ventilation. The result is that after a while, particularly in warm weather, they become sour and unwholesome.

Felt, however, and particularly wool felt, 50 is self-ventilating and sanitary at all times.

It will doubtless be possible to vary the foregoing construction in many detailed respects all within the spirit of the invention and the appended claims. 55

Claims:

1. An artificial limb of the kind described, comprising a hand member having a plurality of fingerlike members, each member consisting in a wire having one end 60 anchored at a point remote from the fingers and a coiled spring portion intermediate the anchored end and the finger end of said wire, felt coverings for each finger and the wire portions in each finger extending beyond the coiled part being tensioned toward each other. 65

2. An artificial hand having fingers each consisting of a spring wire and a covering of felt over said wire, the wire being bent 70 to hold each finger in a gripping position and being sufficiently rigid to maintain each finger in said position under relatively heavy strains tending to straighten it, each of said wires having a coiled portion behind the 75 bent portion to enable said finger to yield, and a thumb coöperating with said fingers and comprising a spring and a covering of yielding material for said spring. 75

3. An artificial limb comprising a hand 80 and a forearm, said hand comprising a plurality of fingers each consisting of a wire and a covering for said wire, said forearm consisting of a hollow sheath-like body made of heavy felt, and said finger wires being 85 extended backwardly along said forearm and anchored to the outer surface of said forearm.

In testimony whereof, I have signed my name to this specification.

JOHN J. EVERSON.
